UNITED STATES PATENT OFFICE

NATHANIEL E. LOOMIS, OF WESTFIELD, NEW JERSEY, ASSIGNEE TO STANDARD OIL DEVELOPMENT COMPANY, A CORPORATION OF DELAWARE

METHOD FOR THE CONDENSATION OF HYDROCARBON VAPORS AND APPARATUS THEREFOR

Application filed July 12, 1927. Serial No. 205,095.

This invention relates to the art of distilling petroleum oils and more specifically to an improved method and apparatus for the condensation of the hydrocarbon vapors evolved on distillation of petroleum oils.

In accordance with my method the vapors to be condensed are passed into indirect heat interchanging relationship with a body of substantially pure water or other completely volatile material of relatively low boiling point and non-corrosive character in relation to the metals in the apparatus employed. The condensation of the hydrocarbon vapors takes place simultaneously with the vaporization of the water or other material which will hereinafter be referred to as the intermediate cooling medium. The vapors thereof are conducted away and passed into indirect heat interchanging relationship with any convenient cooling liquid which may be available and impure or even salt water may be employed for this purpose. The condensed intermediate cooling medium is returned to heat interchanging relationship with the hydrocarbon vapors and continuous circulation established.

The condensed oil is preferably cooled by passing the same into indirect heat interchanging relationship with any convenient cooling medium preferably the cooling liquid passing to the apparatus in which the vapors of the intermediate cooling liquid are condensed.

In the preferred embodiment of my invention the vaporization and condensation of the intermediate cooling medium is conducted under vacuum, an absolute pressure of 10 inches of mercury or less being maintained in the system.

The distillation of petroleum oil and the condensation of the vapors evolved may also be conducted under vacuum, an absolute pressure of 10 inches of mercury or less being preferably maintained therein.

The drawing shows a diagrammatic vertical section of a preferred form of apparatus for carrying out my invention. In this apparatus, 1 is a still for the distillation of petroleum oils mounted on a firebrick

setting 2 and heated in any suitable manner to produce hydrocarbon vapors. A number of stills may be employed either operating separately or as the units of a battery for the continuous distillation of petroleum and the vapors therefrom may be manifolded in any desired combination. The vapors to be condensed pass through vapor line 3 into condenser 4, which carries a number of open end tubes 5 between header plates 6 and 7. The hydrocarbon vapors are confined between the exterior of these tubes and the jacket 8. Fresh water is continuously supplied to the interior of the tubes through the pipe 9 and is evaporated simultaneously with the condensation of the hydrocarbon vapors. If the still and condenser are operated under reduced pressure, uncondensed vapors and non-condensable gases are withdrawn through outlet 10 by means of a vacuum pump 11. This may be of any suitable form although that shown and preferably employed maintains a vacuum by the operation of a jet of dry steam at high velocities and is preferably equipped at the discharge end with a condenser 12 through which cooling fluid is passed by means of inlet 13 and outlet 14. The condensed hydrocarbons pass off through pipe 15 to the heat exchanger 16 in which they are cooled by the circulation of a cooling medium through the multiplicity of open end pipes 17. The cooled oil is transferred by pump 18 through pipe 18^a to tank 19 for storage.

The vapors of the intermediate cooling medium pass continuously into condenser 20 in which they are held between casing 21 and the exterior of a multiplicity of open end tubes 22. Water which may be impure or even salt water is circulated within the tubes whereby condensation of the vapors is effected, the condensate being continuously returned to 8 by pipe 9. That part of the system in which vaporization and condensation of the vapors of the intermediate cooling medium is effected is preferably maintained under vacuum by withdrawing any permanent gases or uncondensed vapors therefrom through pipe 24 by means of the vacuum pump 25 discharg-

ing through condenser 26, the construction of which pump and condenser is similar to 11 and 12 previously described.

It will of course be understood that the 5 apparatus shown is an illustration and that various alternative arrangements and procedures may be adopted within the scope of the appended claims in which it is my intention to claim broadly all novelty inherent 10 in the invention.

10 What I claim is:

1. The process of condensing vapors of petroleum oils which comprises passing such vapors under an absolute pressure of 10 15 inches of mercury or less in heat interchanging relationship to a cooling medium maintained under an absolute pressure of 10 inches of mercury or less to produce condensation of the vapors of petroleum oil and vaporization of the cooling medium, conducting away and condensing the vapors of the cooling medium, and continuously returning the condensate to heat interchanging relationship with the vapors of petroleum oil.

2. The process of condensing vapors of petroleum oils which comprises passing such vapors under less than atmospheric pressure in heat exchanging relationship with a cooling fluid maintained under less than 20 atmospheric pressure.

3. The process of condensing vapors of petroleum oils which comprises passing such vapors under less than atmospheric pressure 25 in heat exchanging relationship with a cooling fluid maintained at substantially the same pressure.

4. The process of condensing vapors of petroleum oils which comprises passing such 30 vapors into indirect heat exchanging relationship with substantially non-corrosive liquid whereby the latter is vaporized, conducting away and condensing the vapors of the liquid by indirect heat exchange with relatively corrosive liquid, and returning the 35 non-corrosive liquid condensate to heat interchanging relationship with the vapors of petroleum oil.

5. The process of condensing vapors of petroleum oils which comprises passing such 40 vapors under less than atmospheric pressure into heat exchanging relationship with substantially non-corrosive liquid whereby the latter is vaporized, maintaining the liquid under less than atmospheric pressure, 45 conducting away and condensing the vapors of the liquid by indirect heat exchange with relatively corrosive liquid, and returning the non-corrosive liquid condensate to heat interchanging relationship with the vapors of petroleum oil.

6. An apparatus for the condensation of 50 petroleum vapors, comprising means for passing such vapors in indirect heat interchanging relationship with a cooling me-

dium, means for maintaining the vapors under pressure less than atmospheric, means for maintaining the cooling medium under pressure less than atmospheric, means for conducting away and condensing the vapors of the cooling medium and for returning the condensate to the heat interchanging relationship.
